UNITED STATES PATENT OFFICE.

JOSEPH GOODMAN, OF NEW HAVEN, CONNECTICUT, ASSIGNOR TO C. COWLES & CO.,
OF NEW HAVEN, CONNECTICUT, A CORPORATION.

HANDLE-LOCK.

1,372,168.

Specification of Letters Patent. Patented Mar. 22, 1921.

Application filed June 10, 1919. Serial No. 303,064.

To all whom it may concern:

Be it known that I, JOSEPH GOODMAN, a citizen of the United States, residing at New Haven, in the county of New Haven and State of Connecticut, have invented a new and useful Improvement in Handle-Locks; and I do hereby declare the following, when taken in connection with the accompanying drawings and the characters of reference marked thereon, to be a full, clear, and exact description of the same, and which said drawings constitute part of this application, and represent, in—

Figure 1 a face view of a handle lock constructed in accordance with my invention.

Fig. 2 a broken side view of the same.

Fig. 3 a broken view in vertical section.

Fig. 4 a face view of the locking pin detached.

Fig. 5 a side view of the same.

Fig. 6 a rear view of the pin tumbler.

Fig. 7 a side view of the same.

This invention relates to an improvement in handle locks, and while adapted for various purposes, is especially designed for automobile doors. In the more general construction of handle locks the locking mechanism is arranged in the handle itself. This necessitates that the handle shall be of sufficient size to contain the locking mechanism and is more or less restricted in design.

In automobile doors the faces are frequently curved or arranged at an angle to the plane of the handle; and the object of this invention is to so connect the escutcheon or front plate that it may conform to the angle of the face of the door without affecting the position of the lock mechanism or handle; and the invention consists in the construction hereinafter described and particularly recited in the claim.

In carrying out my invention I employ a lock casing 10 comprising a handle shank housing 11 and a pin-tumbler cylinder housing 12 connected by a web 30, this casing being mounted in a suitable recess formed for it in the door in which it is held in place by a face plate or escutcheon 13 which may be secured in place by screws

14 and in line between the shank housing and cylinder housing the web is formed with a semicircular recess 15 to receive a correspondingly shaped boss 16 struck inward from the plate 13, this boss forming 55 a seat for a screw 17 which has a head 18 arranged on its under face so as to form a ball and socket joint with a face plate which is thereby adapted to be rocked to correspond to the curvature or angle of the 60 door. The handle 19 may be of any approved design herein shown as of bar type formed with a round shank 20 which fits in the shank housing 11 and with an inwardly extending latch-operating spindle 21. The 65 shank is formed with a locking notch 22 to receive the upper end of a vertically arranged locking pin 23 formed at its lower end with a cam disk 24 having a cam groove 25 which receives the eccentric pin 26 at the 70 inner end of a key cylinder 27 which is mounted in the key housing 12, the key opening being exposed through an opening formed for it in the face plate 13. The knob shank is also formed with a shallow 75 holding recess 28 adapted to receive a spring actuated pin 29 mounted in the web 33, and adapted to yieldingly hold the handle in its normal position when unlocked. To lock the handle the key cylinder is turned 80 to raise the pin 23 so as to force it into the locking notch 22 so as to firmly hold the handle shank against rotation, thus preventing the operation of the latch. The turning of the key cylinder in the usual 85 way draws the pin downward so as to disengage it from the handle shank permitting that handle to be freely turned. By connecting the face plate with the housing as shown, the plate may stand at any desired 90 angle with relation to the casing and form a neat finish for the door. With this arrangement of locking mechanism I am enabled to provide the handle shank with any style of handle desired without changing 95 the other parts of the lock.

I claim:—

A handle lock, the combination with a housing including a shank housing and a pin tumbler lock housing, the front face 100

of the casing formed with a recess, and a face plate formed with a projection in line with, and adapted to enter said recess, and means extending through the face plate into the casing whereby the face plate may be rocked with relation to the casing.

In testimony whereof, I have signed this

specification in the presence of two subscribing witnesses.

JOSEPH GOODMAN.
